(57) **CLAIM**

The ornamental design for vehicle air deflector, as shown and described.

DESCRIPTION

FIG. 1 depicts a front, top, left perspective view of a vehicle air deflector showing our new design.

FIG. 2 depicts a front, bottom, right perspective thereof.

FIG. 3 depicts a front view thereof.

FIG. 4 depicts a back view thereof.

FIG. 5 depicts a left side view thereof.

FIG. 6 depicts a right side view thereof.

FIG. 7 depicts a top view thereof; and,

FIG. 8 depicts a bottom view thereof.

The long-short dash lines depict boundaries of the claimed design. The even dash lines depict portions of the article, such as the do not touch warning icon on the front and the portions of the back, forming no part of the claimed design.

1 Claim, 7 Drawing Sheets
